UNITED STATES PATENT OFFICE

MARCUS R. HARRIS, OF DETROIT, MICHIGAN

CLOSURE OPERATOR

Application filed February 15, 1926. Serial No. 88,277.

The present invention relates to closure operators and specifically to garage doors and means for compensating for the weight thereof.

5 Heretofore, in doors of this type the ordinary method of counterweighting has been to so apply the weight that it exerts a substantially constant effect. With doors arranged to travel upward and then horizontally, so 10 that, when fully opened, the door is supported upon a horizontal track, this form of counterweight is objectionable in that during the latter portion of its travel in opening the weight of the door is very much over- 15 balanced by the counterweight.

In the usual use of springs, the same objection exists.

Among the objects of the present invention, therefore, is to overcome this objection and 20 provide means whereby the effect of the counterweighting varies with the position of the door and is substantially nil when the door is in its horizontal, fully-open position.

With this and other objects in view as 25 will more clearly hereinafter appear, the invention consists in the novel combination of elements illustrated in the accompanying drawing and in such modifications and variations therein as will be obvious or within the 30 skill of those skilled in the art and come within the scope of the claim which is hereunto appended.

In the accompanying drawing illustrating a preferred embodiment of the invention, 35 Fig. 1 shows a side elevation of a door and counterweight with parts in section; and

Fig. 2 is a horizontal section on the line 2—2 of Fig. 1.

In the drawings, the numeral 10 indicates 40 a garage or other building provided with the usual door frame 11. The door 12 is adapted, in closed position, to press tightly against the inner edge of the frame 11 and is opened by lifting it bodily upward and away from 45 the frame.

In order to permit this movement of the door, it is made in several sections 12^a, 12^b and 12^c, as indicated, and each section provided with rearwardly extending arms 13 carrying rollers or trolley wheels 14 cooperat-

ing with tracks 15. These tracks 15 extend upward from near the bottom of the door frame 11, slanting a little toward the rear, to about the top of the frame and then rearwardly in a substantially horizontal position 55 as shown. The arrangement of the tracks in this fashion causes the weight of the door to be supported by the tracks in a greater and greater proportion as it is moved to wide-open position, so that the door lies in substantially a horizontal position almost entirely supported by the horizontal portion of the track.

As doors of this type are usually of considerable weight, they must be counterpoised, 65 and in the present invention the door is counterweighted by means in which the effect is gradually lessened as more and more of the door is supported by the horizontal track.

The counterweight means is shown as a 70 weight 20 fixed upon and adjustable lengthwise of one spoke of a sector 21 of a pulley pivoted at 22 upon a suitable support, means such as the set screw 20^a being provided to secure the weight in adjusted position. The 75 sector is provided with a groove 23 on its curved edge in which is received a rope or cable 24 secured to the sector opposite the weight 20. This cable 24 extends, in the form shown, vertically to a pulley 25 and then horizontally to another pulley 26 and then forward to the center of an equalizer bar 27. At each end of bar 27 other cables 28 extend over pulleys 29 down along the lateral edges of the door to the bottom thereof and are secured to 80 the lower end of the bottom door section.

The cables 24 and 28 are of such length and the radius of the sector such that, when the door is shut, the weighted spoke of the latter is substantially horizontal and the weight 20 90 accordingly exerting its greatest pull, while, when the door is completely open, the weighted spoke is hanging substantially vertical with the cable 24 lying in groove 23.

The adjustability of weight 20 provides 95 means whereby a given sector and weight may be used with different weights of doors.

This arrangement of the counterweight provides the operator of the door with the most assistance when the most or all of the 100

weight of the door must be moved and also offers the least resistance when the weight of the door is almost if not entirely supported by the track, that is, when the door is to be moved from wide-open position.

- 5 It is preferred to arrange the parts as indicated, with a single sector and an equalizer, but it is obvious that two such sectors might be used, one connected to each side of the door.
- 10 It is also obvious that other suitable locations than on the side of the building may be used for the sector.

Further, while the sector shown and described represents a sector of a circular pulley, it is obvious that other shapes may be used, e. g. a portion of an oval or the curved side may be spiral. In these other instances the basic idea is the same and therefore the claim is intended to include such structures

- 20 Within its scope.
- Having now described the invention and the preferred form of embodiment thereof, it is to be understood that the said invention is not to be limited to the specific details herein described and illustrated but only by the scope of the claim which follows.

I claim:

Counterweight means for doors adapted to be lifted from closed position and guided to horizontal open position wherein said doors are supported by the guiding means, said counterweight means consisting of a sector of a grooved pulley having spokes, a weight secured to one of said spokes, and a cable connection from the outer end of said weighted spoke to said door, said cable being of such length that said weighted spoke assumes a horizontal position with the rest of the sector above, when said door is in closed position.
